CLOTHES DRIER

Edward A. Illig, Erie, Pa., assignor of one-half
to Louis Burg, Erie, Pa.

Application September 10, 1937, Serial No. 163,311
Renewed December 17, 1938

1 Claim. (Cl. 211—116)

This invention aims to provide a simple support for garments and other articles which are to be dried, the construction being such that the article may be folded into small compass when not in use, or, if desired, detached from an overhead anchor.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Fig. 1 shows in elevation, a device constructed in accordance with the invention, parts being broken away;

Fig. 2 is a top plan;

Fig. 3 is a bottom plan;

Fig. 4 is a longitudinal section wherein parts appear in elevation;

Fig. 5 is a transverse section taken approximately on the line 5—5 of Fig. 4;

Fig. 6 is a cross section on the line 6—6 of Fig. 4;

Fig. 7 is a section taken approximately on the line 7—7 of Fig. 3, parts being omitted.

In carrying out the invention, there is provided a cup-shaped anchor 1 (Fig. 4) provided in its bottom wall with an opening 2 (Fig. 2), the opening having oppositely disposed extensions 3.

A hanger rod 4 (Fig. 4) is provided. An abutment 5 is secured to the hanger rod 4, near the upper end of the hanger rod. A washer 6 rests on the abutment 5. The lower end of a compression spring 7 engages the washer 6. The upper end of the compression spring 7 engages a washer 8 slidable on the hanger rod 4. Close to its upper end, the hanger rod 4 has lateral projections 9, which may be the ends of a cross pin.

A foot 11 is threaded on the lower end of the hanger rod 4 and has a transverse slot 12. In the slot 12 is received the thinned end 14 (Fig. 3) of a support 15. The thinned end 14 of the support 15 is pivoted at 16 to the lower end of the foot 11. The upper end of the foot 11 forms a shoulder 34 on the rod 4, near the lower end of the rod.

A tubular main slide 17 is mounted for reciprocation with respect to the hanger rod 4, and, specifically, on the foot 11 of the hanger rod. A sleeve 18 is fixed in the upper end of the tubular slide 17 and fits closely but slidably about the hanger rod 4. The lower end of the sleeve 18 forms a shoulder 19 within the slide 17.

An inverted cup-shaped head 20 is threaded and fixed upon the upper end of the main tubular slide 17. The head 20 is provided at its lower end with an outstanding flange 21, which constitutes an arm rest, as will be explained hereinafter. There are slots 22 in the side wall of the head 20 and in the upper wall of the head. A cap 23 is threaded on the lower end of the main slide 17 and is fixed thereon. The cap 23 forms a stop, as will be explained hereinafter. The hanger rod 4 and the foot 11 can slide downwardly through the cap or stop 23. The upper end of the cap or stop 23 forms a shoulder 24.

The numeral 25 marks an auxiliary slide mounted to reciprocate on the main slide 17. The auxiliary slide 25 comprises a depending tubular neck 26 carrying a disk-like top member 27. A cap disk 28 is superposed on the top member 27 of the slide. The cap disk 28 is attached to the top member 27 of the slide 25 by securing elements 29. In their peripheries, the cap disk 28 and the top member 27 have registering notches 30. In the abutting surfaces of the cap disk 28 and the top member 27 of the slide 25 there are cooperating notches, defining openings 31 (Fig. 7).

The openings 31 receive pivot elements 32. The lower ends of arms 33 are mounted to swing on the pivot elements 32 and are located in the notches 30. The arms 33 extend upwardly through the slots 22 of the head 20.

The support 15, in practical operation, is disposed crosswise of the hanger 4 and the cap 23 rests on it, though shown spaced from it in Fig. 4, for clarity of illustration. Thus the main slide 17 and parts connected with it are supported, substantially as shown in Fig. 1. The auxiliary slide 25 is supported because the lower end of the neck 26 thereof rests on the cap or stop 23 of the main slide 17. The arms 33 extend upwardly through the slots 22 in the head 20 on the upper end of the main slide 17, and cannot swing downwardly on the pivot elements 32, since the arms are restrained against such movement by the arm rest 21 of the head, reference being had to the solid line positions of Fig. 4.

The operator inserts the upper end of the hanger 4 through the opening 2 of the anchor 1,

the projections 9 on the hanger passing upwardly through the extensions 3 of the opening 2. The hanger 4 is given a quarter turn, and, thus, the projections 9 engage above the bottom wall of 5 the anchor 1, as in Figs. 4 and 2, the hanger and associated parts thereby being detachably suspended from the anchor. The spring 7 presses downwardly on the abutment 5 which is secured to the hanger 4, and upwardly on the slide washer 10 8, the washer engaging the lower end of the anchor 1 and forming a friction brake which prevents the hanger 4 from rotating and becoming detached from the anchor.

The support 15 is swung on the pivot element 15 16 into alignment with the hanger 4. The tubular slide 17 and parts associated with it are slid downwardly, in the position of Fig. 4, until the shoulder 19 at the lower end of the sleeve 18 engages the shoulder 34 at the upper end of the 20 stop cap 23 on the lower end of the slide 17. The auxiliary slide 25 is moved upwardly to the dotted line position of Fig. 4, and the arms 33 move upwardly through the slots 22 of the head 20, and swing outwardly on the pivot elements 32, until 25 the arms assume a horizontal position, supported by the arm rest 21. The slide 17 and parts connected to it may be rotated on the hanger 4, to dispose the arms 33 in convenient relation to a person who wishes to hang something upon them.

30 The operator can detach the hanger rod 4 and connected parts from the anchor 1, leaving the

anchor, only, in place on the ceiling of a room. If the operator wishes, he can leave the parts in the position of Fig. 4, with the arms 33 folded. If he desires, he can move the slide 17 down on the hanger rod 4 and open out the arms 33. 5

Having thus described the invention, what is claimed is:

In a device of the class described, a hanger, a tubular main slide mounted to reciprocate on the hanger, an arm rest fixed to the upper end 10 of the main slide, the hanger and the main slide having fixed vertically spaced shoulders, means on the lower portion of the hanger, below the main slide, for holding the main slide against downward movement on the hanger, an auxiliary 15 slide mounted to reciprocate on the main slide and engaged with the main slide against downward movement, arms passing slidably through the arm rest and held upwardly folded by engagement with the arm rest, the lower ends of the 20 arms being pivoted to the auxiliary slide, said means being releasable to permit the main slide to move downwardly until the shoulders of the hanger and of the main slide engage, the auxiliary slide then being upwardly movable, to raise 25 the arms through the arm rest and permit them to swing outwardly and downwardly until they assume a substantially horizontal position, supported by the arm rest.

EDWARD A. ILLIG. 30
